SLEEPING BAG

John Corrao, New York, N. Y.

Application January 23, 1948, Serial No. 143,997

Term of patent 3½ years

(Cl. D92—2)

To all whom it may concern:

Be it known that I, John Corrao, a citizen of the United States, residing at New York, in the county of New York and State of New York, have invented a new, original, and ornamental Design for a Sleeping Bag, of which the following is a specification; reference being had to the accompanying drawing, forming a part thereof.

In the drawing:

Fig. 1 is a perspective view of a sleeping bag, showing my new design in open position;

Fig. 2 is a similar view showing the same in closed position; and

Fig. 3 is a rear perspective view of the same.

I claim:

The ornamental design for a sleeping bag, as shown.

JOHN CORRAO.
